UNITED STATES PATENT OFFICE.

JAMES L. COX, OF BERGHLZ, OHIO.

REPEATING SHOTGUN.

1,355,316.

Specification of Letters Patent. Patented Oct. 12, 1920.

Application filed May 15, 1919. Serial No. 297,189.

To all whom it may concern:

Be it known that I, JAMES L. Cox, a citizen of the United States, residing at Bergholz, in the county of Jefferson and State 5 of Ohio, have invented a new and useful Repeating Shotgun, of which the following is a specification.

The invention relates to new and useful improvements in repeating shot guns and 10 more especially to a safety device to be used in combination with a repeating shot gun constructed in accordance with my Patent No. 1,111,440, dated September 22, 1914.

The object of the invention is to prevent 15 the hammer from being released and thrown against the firing pin at any time excepting when the breech block is locked.

A further object is the provision of a 20 safety lock for locking the hammer, where- as in the usual form of shot gun the safety devices are arranged to lock the trigger.

With these objects in view the invention 25 consists in the novel construction and arrangement of parts, hereinafter described, illustrated in the accompanying drawings, and particularly pointed out in the appended claims, it being understood that various changes in the form, proportions, size and minor details of construction may be made 30 within the scope of the appended claims, without departing from the spirit or sacrificing any of the advantages of the invention.

The invention thus set forth in general 35 terms is illustrated in the accompanying drawings forming part hereof, in which—

Figure 1 is a side elevation of a portion of a gun made in accordance with the invention.

Fig. 2 an enlarged view in elevation with one side of the casing removed, showing the breech block in the locked position and the hammer released.

Fig. 3 a similar view showing the breech block in the position assumed just prior to being locked.

Fig. 4, a section on line 4—4, Fig. 3; and

Fig. 5, a similar view showing the breech block in the locked position and the hammer 50 in the cocked position.

A practical embodiment of the invention is disclosed in the accompanying drawings, forming a part of this specification, in which similar numerals of reference indi-

cate corresponding parts throughout the 55 several views.

The operating parts of the breech mechanism are contained in the casing 1, the barrel being designated by the numeral 2 and the forward stock section which incloses 60 the magazine 3 is designated by the numeral 4. The breech block 5 is mounted within the chambered portion of the casing and is shown in Fig. 2 in its locked position and in Fig. 3 is illustrated in the position it 65 assumes just prior to being locked.

The usual sliding handle 6 is mounted upon the lower portion of the forward part of the stock and is arranged to reciprocate the action bar 7 which is mounted to have a 70 reciprocating movement within the recess 8 formed in the face of the casing, said action bar being connected by means of a pin 9 passing through registering apertures in the walls of the handle and connected to the 75 action bar, said pin passing through elongated registering slots 10 formed in the forward stock portion 3 and serving to guide the handle in the operation of the gun.

The rear end of the action bar is provided 80 with a suitable aperture, which engages the pin 11 which is carried by the breech locking lever 12. The member 12 is forked, forming two arms 13 pivotally mounted upon a pin 14, which passes 85 through the breech block.

The breech block is provided with recesses 15 upon opposite sides thereof in which the arms 13 of the breech locking lever are positioned, the rear end of said locking member 90 having a hooked shaped projection 16 which serves as a means of protecting the firing pin 17 when the breech block is driven rearwardly to receive a shell to be fed forward into the breech of the gun.

One face of the breech block is provided 95 with a recess 18 to receive a resilient shell extracting trigger 19. The locking member 12 is provided with a cam shaped projection 20 upon its free end which terminates 100 at one end in an inclined shoulder 21 for purposes which will be hereinafter described.

The tilting shell lifting member 22 is pivotally mounted upon the pin 23 and is provided 105 near its forward free end with an elongated slot 24, through which slot a lifting finger 25, pivoted at 26, is located, the

purpose of this finger being to elevate the rear end of the shell while the latter is being raised to a position to be driven forward by the breech block into the breech, thereby avoiding jamming of the shell.

A resilient cartridge stop 27 is fastened to a pin 28 at its rear end and is positioned in a recess at the forward end of the shell lifting member. The forward end of the cartridge stop is adapted to engage the rim 29 of a shell 30 within the magazine to cause the shell to be released from the magazine when it is desired to deliver the same into the barrel of the gun. Pivotaly mounted upon a pin 31 carried by the rear end of the shell lifting member is a pawl 32, a spring 33 bearing against the wall of the recess 34 and against the pawl to normally hold the pawl at its farthest inner throw so that the upper edge thereof will be deposited in the path of the inclined shoulder 21 when the breech block is thrown back from its forward position, allowing the pawl to swing out idly, without causing the shell lifting member to be tilted.

It will be noted that the pawl has its upper rear edge inclined at 35 against which the inclined edge 36 of the cam shaped projection 20 is adapted to contact as the breech block is moved forward from its rearmost position, thus causing the forward end of the shell raising member to be thrown up for the purpose of raising a shell previously withdrawn from the magazine to a position to be driven into the barrel on the forward movement of the breech block.

During the tilting of the shell raising member, the finger 25 before referred to is thrown to an inclined position and coming in contact with the rear portion of the shell will tend to lift the same up to a position in alignment with the barrel so as to avoid any possibility of the cartridge jamming when driven forward by the breech block.

The breech block is driven forward and the projecting portion 37 thereof comes into contact with the shoulder 40 and a further forward movement of the sliding handle 6 will cause the action bar to move therewith and as the rear end of said bar is pivotally connected with the locking block 12 the latter will be caused to swing first into the position illustrated in Fig. 3 and then to the position shown in Fig. 2 with the convex or cam edge 41 of said locking block in contact with the upper edge of the lug 42, which is carried by the lower wall of the casing. This swinging movement of the locking block will throw the rear end of the breech block into the position shown in Fig. 2 in which its upper end will bear against the shoulder 44 thus forming an abutment means for the breech block.

The hammer 45 is pivotally mounted upon a pin 46, the lower part 47 of the hammer

projecting through a slot in the bottom of the casing. The trigger 48 is pivotally mounted upon a pin 49 and is provided with an ear 54 at its upper extremity, the purpose of which will be later described. A hammer spring 51 is fastened at one end to the bottom of the casing and engages a notch 52 formed in the edge of the hammer. The hammer is provided with a shoulder 53 on its rear side which engages the shoulder 50 at the upper end of the trigger in the manner shown in Fig. 3 of the drawings, holding the hammer in the cocked position.

The forward end of the shell lifting lever 22 is slightly inclined as at 55 and is designed to engage and depress the shell holding member 27 when the breech block is at its forward limit to allow a shell to be driven by the spring plunger 56 within the magazine to a position to be raised by said shell lifting member. This action of the tilting shell lifting member to release a shell in the magazine by the depression of the member 27 is substantially simultaneous with the locking of the breech block.

The side of the casing is provided with an opening 60 through which opening the shells are placed within the casing as they are fed into the magazine and through which opening the shells are thrown out after being fired. A closure 62 to said opening is fastened to the breech block and moves therewith and automatically opens as the breech block is thrown rearward and closes as the block is moved forward in the act of delivering the shell into the barrel.

It should be noted that upon the forward movement of the sliding handle it will be impossible for the hammer to strike the firing pin by reason of the hooked shaped projection 16 of the locking member forming an abutment surface against which the hammer would contact, thus producing a safety device which will positively insure the hammer against engaging the firing pin until the breech block and breech locking member have assumed the position shown in Fig. 3. In this position the breech is not quite locked and it would be possible for the hammer to contact with the firing pin discharging the shell with the breech unlocked, which would not only probably damage the gun but would be exceedingly dangerous to the person firing the gun or those near by. In order to prevent accidental discharge of the shell at any time while the breech block and breech locking member are in any position between that shown in Fig. 3 and the locked position shown in Fig. 2, a safety device is provided, which comprises a U-shaped member having the arms 64 and 65 and pivoted at 66 to the extension 54 upon the trigger. These arms are slidably mounted in slots 67 and 68 respectively in the block 42 and a coil spring 69 is provided around the arm 64 interposed

between the head 70 of the U-shaped member and the block 42 tending to normally urge the U-shaped member into the position shown in Fig. 2. The free extremity of the 5 arm 64 is inclined downwardly as shown at 71 and the free extremity of the arm 65 is beveled as shown at 72.

As shown in the drawings the block 42 is provided with a transverse passage 73 with- 10 in which is pivotally mounted the locking member 74 having the upwardly projecting finger 75 and the outwardly projecting finger 76 provided with a beveled side edge 77.

15 As the breech locking member 13 comes into the position shown in Figs. 3 and 4 the cam shaped projection 20 thereon will engage the finger 75 rocking the locking member 74 against the pressure of the spring 77' 20 and forcing the finger 76 into a substantially horizontal position as best illustrated in Fig. 4. It will be seen that no amount of pressure upon the trigger 48 can move the trigger to release the hammer as the beveled extremity of the arm 65 is engaged by the 25 beveled side edge of the finger 76 of the locking member preventing any movement of the trigger.

As the breech locking member 13 is moved 30 into the locked position shown in Fig. 5 the cam shaped projection 20 will be moved beyond the finger 75 of the locking member 74 allowing the spring 77' to tilt the locking member into the position shown in Fig. 35 5. The finger 76 is thus raised out of engagement with the extremity of the arm 65 allowing the trigger to be pulled.

As the trigger is pulled and the hammer 40 released the spring 69 will throw the U-shaped member into the position shown in Fig. 2 upon release of the trigger, the inclined extremity 71 of the arm 64 engaging the finger 76 of the locking member 74 and rocking said locking member into the position shown in Fig. 4, thus moving the finger 75 thereof out of the path of the cam shaped projection 20 as the breech block is moved to its rearward position.

For the purpose of locking the hammer 50 as a safety means when the gun is loaded a hook 78 is pivoted at 79 and normally held in the inoperative position, as shown in Fig. 3, by means of a spring 80. When it is desired to lock the hammer, the hook member 55 78 is pressed rearward into the position shown in Fig. 1, engaging the lower part or finger piece 47 of the hammer. It should be noted that this finger piece 47 will be slightly raised by this engagement with the hook member 78, thus releasing the trigger of the function of holding the hammer in the cocked position. With the hammer thus locked the trigger may be pulled but the hammer will not be released.

65 It will be understood that although the

device herein disclosed and described is illustrated and described as applied to a repeating shot gun, that it is adaptable to a repeating rifle or any repeating small arm having a sliding breech block, a hammer and a trigger for controlling the operation of 70 the hammer.

I claim—

1. A repeating firearm including a sliding breech block, a hammer, a trigger to hold 75 the hammer in cocked relation, a sliding arm connected to the trigger and provided with a beveled forward end, a pivoted locking member provided with a beveled face corresponding with the beveled end of the 80 arm and means controlled by the operation of the breech block for moving the locking member into engagement with the sliding arm.

2. A repeating firearm, including a sliding 85 breech block, a hammer, a trigger to hold the hammer in cocked relation, a sliding arm connected to the trigger, a pivoted locking member provided with a finger arranged to be thrown in the path of said 90 sliding arm and a breech block locking member controlling the operation of said locking member.

3. A repeating firearm including a sliding 95 breech block, a breech locking member connected thereto, a hammer, a trigger to hold the hammer in cocked relation, a sliding arm connected to the trigger, and a pivoted locking member provided with a finger arranged to engage said sliding arm and a second finger 100 arranged to be engaged by said breech locking member.

4. A repeating firearm including a sliding breech block, a breech locking member connected thereto, a hammer, a trigger to hold 105 the hammer in cocked relation, a U-shaped member, comprising a long arm and a short arm, connected to the trigger, a cam portion upon the long arm, a spring for returning the trigger to the normal position and a pivoted locking member comprising a finger 110 arranged to engage said short arm and a finger arranged to be engaged by said breech locking member, the cam portion upon said long arm arranged to engage said first 115 named finger when the trigger is in the normal position.

5. A firearm having a trigger guard and including a hammer provided with a finger piece extending within the trigger guard, 120 a trigger to hold the hammer in cocked position and a spring pressed, pivoted hook extending through an aperture in the trigger guard and arranged to engage the finger piece to lock the hammer in cocked position. 125

6. A repeating firearm including a sliding breech block, a breech locking member connected thereto, a trigger to hold the hammer in cocked relation, a U-shaped member comprising a long arm and a short arm con- 130

nected to the trigger, a spring for retaining the trigger to the normal position and a pivoted locking member arranged to engage the short arm and arranged to be engaged by the breech locking member, the long arm arranged to engage said pivoted locking member when the trigger is in the normal position.

7. A repeating firearm including a sliding breech block, a breech locking member connected thereto, a hammer, a trigger to hold the hammer in cocked relation, a sliding member connected to the trigger, a cam upon said arm, a spring for returning the trigger to the normal position and a pivoted locking member comprising a finger arranged to engage said sliding member and a finger arranged to be engaged by said breech locking member, the cam upon said sliding mem-

ber being arranged to engage the first named finger when the trigger is in the normal position.

8. A repeating firearm, including a sliding breech block, a breech locking member connected thereto, a hammer, a trigger to hold the hammer in cocked relation, a sliding member connected to the trigger, a cam portion upon the sliding member, and a pivoted locking member arranged to engage said sliding member and to be engaged by said breech locking member, the cam portion upon said sliding member being arranged to engage the pivoted locking member when the trigger is in the normal position.

In testimony that I claim the above, I have hereunto subscribed my name.

JAMES L. COX.
